UNITED STATES PATENT OFFICE.

V. MUMFORD MOORE, OF RAVENSWOOD, ILLINOIS.

DOOR-LOCK.

SPECIFICATION forming part of Letters Patent No. 289,435, dated December 4, 1883.

Application filed May 1, 1883. (Model.)

To all whom it may concern:

Be it known that I, V. MUMFORD MOORE, of Ravenswood, in the county of Cook and State of Illinois, have invented certain new and useful Improvements in Door-Locks; and I do hereby declare that the following specification, taken in connection with the drawings furnished and forming a part of the same, is a clear, true, and complete description of the several features of my invention.

My said improvements are applicable to so-called "cottage-locks," as well as to mortise-locks; but some of the features of my invention have special value in mortise-locks.

My said improvements relate, generally, to that class of locks which are inaccessible for unlocking from the side opposite to that at which they have been previously locked; but they relate more particularly to that special class of such locks which embody in their cases a central partition and separate or independent tumblers or sets of tumblers so isolated from each other by said partition that lock-picking devices entered from either side of the lock can only be engaged with one of said tumblers or sets of tumblers. Of the said centrally-partitioned locks, some have embodied one or more tumblers on each side of the bolt, all so connected together as to be moved as one tumbler when actuated by a key entered from either side of the lock, and there has been employed therewith, for approximately obtaining the purposes intended, a pair of auxiliary non-gated tumblers or catches—one on each side of the central partition, and arranged to be independently operated by a key when used for throwing the bolt; and with reference to this class of locks, mine are radically different, in that I obviate the necessity for auxiliary tumblers or catches, although I can employ them, if desired; and my gated bolt-tumblers at each side of the lock are independent of those on the other side; and when those at one side have been actuated by a key for throwing the bolt forward, those at the other side of the lock are incidentally rendered immovable on their pivots. Another and older variety of said centrally-partitioned locks have embodied a pair of independent gated tumblers so organized that no auxiliary tumblers or catches are necessary.

In these prior locks the gated tumblers are necessarily mounted upon the bolt, and one of them is carried by said bolt whenever actuated by a key for locking and unlocking; but meantime the tumbler on the opposite side of the lock invariably remains in its normal position, while the bolt and the other tumbler are moved forward and back, which mode of operation necessitates a slotted or sliding pivotal connection between both of the gated tumblers and the bolt. My locks differ from those last described, in that my gated bolt-tumblers may either be pivoted to the bolt, so that both will always move therewith, or pivoted to the case, so as to have only a vibrating or rocking movement; and I am therefore enabled to obviate sliding or slotted pivotal connections with their attendant disadvantages, and to employ pivots which are stationary or fixed with relation to the tumblers mounted thereon, thus providing for a simple, durable, and economical construction. In my locks I employ, as a novel feature, a bolt which is centrally slotted vertically and longitudinally, so as to locate one half of its tail or shank on one side of the partition and the other half on the opposite side, thus enabling the extension of the partition above the plane of the bolt, and thereby to completely isolate either side of the lock from the other; and, moreover, the partition serves as a longitudinal guide for the bolt. I also employ a catch for confining the bolt within its case, and said catch is so constructed and the separate tumblers so arranged with reference to said catch that when a true key is introduced at either side of the lock and turned for throwing the bolt forward, said catch is caused by the tumblers to retire from the bolt and leave the latter free to be moved forward; or the bolt-catch may be so arranged as to require no direct lifting action by the tumblers or the key, and, with its spring, be relied upon for accelerating the terminal movements of the bolt in either direction in a manner well known.

To more particularly describe my invention, I will refer to the accompanying drawings, in which—

Figure 1 is a side view of my lock with the side of its case removed and the bolt within the case.

Fig. 2 is a similar view of the opposite side of the lock with its bolt thrown forward. Fig. 3 is a lateral vertical section of the lock, Fig. 1, on line *x*. Fig. 4 is a view of the bolt detached. Fig. 5 is an interior side view of the lock-case, the working parts of the lock having been removed therefrom. Fig. 6 is a lateral vertical section of the case on line *y*, Fig. 5. Fig. 7 illustrates a modification in the construction and arrangement of the tumblers and stumps in accordance with my invention. Figs. 8 and 9 are vertical transverse sections of my lock-case, illustrating the partition adjacent to the key-holes as arranged to furnish end bearings for solid-stem keys. Fig. 10 is a modification of the bolt and its catch, whereby the spring of the latter serves to accelerate the terminal movements of the bolt in both directions.

It is to be understood that my improvements may be embodied in a case otherwise adapted for the reception of knob-latch mechanism, although the lock illustrated by me is unprovided therewith, and also that, although I have shown a mortise-lock, my improvements are equally applicable to those well known as "cottage" or "outside" locks. For the purposes of illustration I have selected simple types of gated tumblers, and show but one tumbler for service on each side of the lock; but it is to be understood that said tumblers may be employed in any desired number, of any desired degree of complexity, and arranged to operate variously with reference to the bolt and to their stumps without material departure from my invention.

The lock-case *A* has two removable sides, *a*, because each side should be accessible for conveniently mounting the working portions of the lock in the case, and each of said sides has a key-hole, *a'*. In its best form my lock has the key holes coincident with each other, so that in setting a mortise-lock the holes in a door may be worked through and through at less cost in time and labor than if said holes were not oppositely located.

The central partition, *b*, so far as relates to dividing the lock-case opposite the key-holes, is substantially as heretofore; but I believe it to be new to extend said partition, as shown, into and across the plane traversed by the bolt, so as to completely isolate one side of the lock from the other, and also so as to enable the partition to serve as a longitudinal guide for the bolt.

As indicated in Fig. 5, the portions of the partition respectively indicated at *b'* *b'* *b* within the adjacent dotted lines are serviceable. The portion *b'*, opposite the key-holes, serves not only as shield or guard, but it serves as a standard for supporting the spindles used in connection with a barrel or hollow key, or for bearings for the end of a spindle-key, as illustrated at *b* in Figs. 8 and 9. The portion at *b* serves as a standard for oppositely-projecting stumps, as in Fig. 1, and the portions *b*

serve as guide-bearings or supports for the bolt.

The bolt *B*, as shown, has a solid head, *c*, but it is divided back of its head by a longitudinal slot into two tail-pieces, *c'* *c*', so that when the bolt is in position there is a tail-piece on each side of said partition, and the latter, at the rear end of the lock, affords guide-bearings on each side for the tail-pieces. At the front end of the lock the partition is cut away, so that the solid head can enter the case.

It will be obvious that the partition *b* can be slotted from front to rear on a line with the central longitudinal line of the bolt, and that the latter in that case need only be grooved either on its upper or lower sides, or both, without impairing the operation of the bolt or the efficiency of the partition for the purposes stated.

As shown in Figs. 1 and 2, the gated tumblers *d* and *d'* are respectively pivoted to the sides of the tail-pieces *c'* *c*', and each is provided with a spring, *e* *e'*, so that as the bolt is moved longitudinally the tumblers are carried with it. In this case, therefore, the stationary stumps *f* *f'* are required for interlocking with the tumblers in a manner well known. The two stumps in this case are the opposite ends of a piece of wire firmly mounted in the partition; but they may be cast integrally therewith, if desired. The lock shown in Figs. 1 and 2, being arranged for a barrel-key, is provided with key steps or spindles *g* *g'*, which are in this case the opposite ends of a piece of wire or rod firmly mounted in the partition.

It will be seen, as indicated in dotted lines in Fig. 1, that as the bolt is thrown forward by a key entered on one side of the lock the idle or inactive tumbler on the opposite side passes freely beneath its stump, while the tumbler in service is placed by the key in line with its stump, and is carried forward with the bolt until it can be properly interlocked with said stump for securely maintaining the bolt in its locked position. In locking and unlocking, the tumbler in service is actuated as in ordinary locks, the inactive or idle tumbler meantime simply moving with the bolt, and when its movement therewith ceases it is located so far beneath the stump *f* that the latter incidentally serves as a stop or abutment, whereby said inactive tumbler is rendered practically immovable on its pivot.

In order that the bolt may be reliably confined within the case, so that it may not be jarred outward, as by the slamming of a door, a bolt-catch, *h*, is applied in such a way as to be normally engaged with the bolt, and so that the key entered from either side will first relieve the catch before moving the bolt. This catch may be variously constructed and arranged; but I have in Figs. 1 and 2 illustrated it as arranged to be released by either of the tumblers when they are tilted or moved by their key preliminary to throwing the bolt. The bolt-catch *h* is in the form of an arm piv-

oted at one end to the lock-case over the central line of the bolt, and its free end, dropping downward, enters and occupies a transverse notch or recess in both tail-pieces and extends beyond each side of the bolt, so as to overhang the vertical plane in which the tumblers are moved. This catch may operate by gravity alone, it being inclined, and its lower end heavy enough to cause it to fall freely after it has been lifted; or it may be backed up by a suitable spring, as shown at *h'*. It will be seen that the upper edge of either tumbler will by coming into contact with the overhanging portion of the bolt-catch lift it out of the recess in the bolt, and leave the latter free to be moved forward by its key. The bolt-catch may be constructed as illustrated in Fig. 10, wherein the bolt *B* has two recesses or notches and an intervening convex surface, over which the catch rides freely, and so that its spring serves to accelerate the terminal movements of the bolt in either direction. In this case the tumblers need not engage with the catch; but it is to be understood that I make no claim to said catch, except in combination with independently-operated tumblers, and so arranged that it will be released from the bolt by the lifting action of either of said tumblers. It is also to be understood that while I disclaim gated bolt-tumblers which have, as heretofore, been connected to a bolt by slotted or sliding pivotal connections, I do not limit myself to any particular type of gated tumblers, nor to such as are mounted on or carried by the bolt, provided, always, that said tumblers are gated for the reception of stumps, and their pivots are fixed or stationary with relation to said tumblers, it being obvious that variations therein may be widely made without in any manner affecting the results sought by me—as, for instance, in Fig. 7 I illustrate pivoted gated tumblers *d*, secured to the rear end of the lock-case, the bolt *B* having on each side thereof a stump, *f*, with which its tumbler interlocks, substantially as before described; and this form of tumbler can operate the bolt-catch, if desired, and the stump passes as freely away from an idle or inactive tumbler as the tumblers pass beneath the stationary stumps in Figs. 1 and 2; and with both arrangements of

gated tumblers the bolt-stumps *f* incidentally serve as stops for locking the inactive tumblers against rotation on their pivots, thus rendering them secure against vertical movement, as when tampered with for inspection; and both forms of tumbler have pivots which are fixed with relation thereto, as distinguished from the prior slotted or sliding pivotal connections hereinbefore referred to.

Having thus described my invention, I claim as new and desire to secure by Letters Patent—

1. The combination, with a lock-case having key-holes at each side thereof, and a central longitudinal partition adjacent to said key-holes, of a sliding bolt, independent gated tumblers or sets of gated tumblers at each side of said partition, and pivots for said tumblers, which are fixed or stationary with relation thereto, substantially as described. 65

2. The combination, substantially as hereinbefore described, of a lock-case having a key-hole in each side thereof, a central partition opposite said key-holes, and a bolt having a longitudinal slot which is occupied by the partition, whereby said partition wholly isolates 75 one side of the lock from the other, and also serves as a longitudinal guide for the bolt, as set forth.

3. In a lock capable of being locked from either side thereof and to be unlocked only from the locked side, the combination of separate bolt-stumps, and oppositely-located independent gated tumblers having pivots which are stationary or fixed with relation to said tumblers, substantially as described, whereby 85 when a tumbler is actuated by a key it will interlock with one stump, and the opposite tumbler and stump be free from liability of contact with each other, as set forth.

4. The combination, in a lock, of the bolt, 90 two independent tumblers or sets of tumblers separately accessible to a key from opposite sides of the lock, and a bolt-catch which is normally engaged with the bolt, and is disengaged therefrom by either of said tumblers or 95 sets of tumblers, substantially as described.
